UNITED STATES PATENT OFFICE.

CLARENCE DAVID RYKER, OF GALENA, ARKANSAS.

PITCHFORK AND RAKE.

1,034,306.

Specification of Letters Patent. Patented July 30, 1912.

Application filed January 24, 1912. Serial No. 673,032.

To all whom it may concern:

Be it known that I, CLARENCE D. RYKER, a citizen of the United States, residing at Galena, in the county of Howard and State 5 of Arkansas, have invented new and useful Improvements in Pitchforks and Rakes, of which the following is a specification.

This invention provides an implement embodying two tools, such as a pitch fork 10 and a rake, the implement embodying a fork which is pivotally connected to the handle and means for securing the fork in an adjusted position, thereby admitting of the relative inclination of the fork to the 15 handle being adjusted so that the angle of the fork to the handle may be changed to suit the operator or to convert the fork into a rake when it is desired to use the implement in such capacity.

20 The invention resides more especially in the peculiar joint formed between the fork and handle and in the means for securing the fork in the adjusted position, the parts being of such formation as to insure a durable and strong joint at all adjustments of the fork.

30 The invention consists of the novel features, details of construction and combination of parts, which hereinafter will be more particularly set forth, illustrated in the accompanying drawing, and pointed out in the appended claim.

35 Referring to the drawing, forming a part of the specification, Figure 1 is a perspective view of the implement as adapted for use in the capacity of a pitch fork. Fig. 2 is a perspective view of the implement as it appears when adapted for use as a rake. Fig. 3 is a perspective view of the tang portion 40 of the fork. Fig. 4 is a perspective view of the metal end of the handle.

45 Corresponding and like parts are referred to in the following description, and indicated in all the views of the drawing, by the same reference characters.

The fork 1 may be of usual construction and has a tang 2 which is formed upon one side with a rib 3 which is slightly widened at its inner end and formed with a transverse opening 4 to receive the pivot fastening 5 connecting the fork and handle. The shoulders 6 are formed at the inner end of the rib 3 and at each side thereof. The tang 2 is depressed at its inner end, as indicated 55 at 7, the depression being rounding to re-

ceive the rounded end of the part of the handle pivoted to the fork. In the preferable construction the fork, tang and rib are of integral formation.

The handle consists of a metal end and a 60 wooden pole or bar, the latter being secured to the metal end in any manner. The metal end of the handle comprises a ferrule 8 and a shank 9, the latter having a recess 10 in one side to receive the rib 3 and having its 65 outer end notched, as indicated at 11, to form a fork which embraces opposite sides of the inner end of the rib 3 to which the fork members are pivoted by means of the fastening 5. The outer end of the forked 70 end of the shank 9 is made rounding to snugly fit the depressions 7 at the sides of the rib 3 formed in the inner end of the tang 2. When the fork is turned into position to aline with the handle, as indicated 75 in Fig. 1, the rib 3 enters the recess 10, thereby forming a substantial and laterally braced joint. The fork members of the shank 9 are formed with transversely alined openings 12 through which the pivot fas- 80 tening 5 passes.

Braces 13 of like formation are located upon opposite sides of the joint and are pivotally connected at one end to the extremity of the tang 2 and have adjustable 85 connection at the opposite end with the handle. Each of the braces 13 has a longitudinal slot 14 to receive a bolt 15 passed transversely through an opening formed in the handle, said bolt also serving to connect 90 the bar portion of the handle with the metal end. Teeth 16 are formed along the outer side of each brace and engage corresponding teeth upon the inner side of a washer 17 mounted upon the projecting portion of the 95 bolt 15. By this means the brace is prevented from slipping when the parts are adjusted and the bolt 15 is properly tightened. The outer ends of the braces 13 are slightly curved to admit of the braces lying 100 close against the sides of the handle when the fork is in line with the said handle. The bolt 15 is provided at one end with a head and its opposite end has a thumb nut 18, which when tightened causes the teeth of 105 the washers 17 to engage with the teeth of the braces 13. A pin 19 pivotally connects the outer ends of the braces to the tang 2.

When the implement is to be used as a pitch fork the parts are in substantial aline-

ment, as indicated in Fig. 1, but when the implement is to be used as a rake the fork is turned approximately at a right angle to the length of the handle and is secured in such position by means of the braces 13 and fastening means 15 and 17 in the manner stated. The construction is such as to admit of adjusting the fork to the handle so that the implement may be adapted to the convenience of the user according to the particular work to be performed.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:—

An implement of the character specified comprising a fork having a tang, a handle pivoted at its extremity to the inner end of the tang, braces arranged upon opposite sides of the handle and having their outer ends slightly curved and pivotally connected to the outer end of the said tang, each of the braces having a longitudinal slot and having their outer faces toothed, a bolt extending through the handle and through the slots of the braces, washers mounted upon the end portions of the bolt and toothed upon their inner faces to engage with the toothed portions of the braces, and means for tightening the bolt to hold the toothed portions of the washers and braces in engagement.

In testimony whereof I affix my signature in presence of two witnesses.

CLARENCE DAVID RYKER.
